UNITED STATES PATENT OFFICE.

LEWIS M. HULL, OF MOUNTAIN LAKES, AND RICHARD W. SEABURY, OF BOONTON, NEW JERSEY, ASSIGNEES TO RADIO FREQUENCY LABORATORIES, INCORPORATED, OF BOONTON, NEW JERSEY, A CORPORATION OF NEW JERSEY.

INDUCTIVE-COUPING DEVICE.

Application filed December 27, 1922. Serial No. 609,230.

This invention relates to devices employed for the inductive coupling of electric circuits and more particularly to inductive coupling devices of the type comprising a stator and rotor.

It is an object of the invention to provide an inductive coupling device in which the maximum efficiency is attained by reducing the clearance between the stator and rotor windings to a minimum. An object of the invention is to provide an inductive coupling device having two windings and in which the leakage of magnetic flux between the windings is reduced to a minimum. A further object is to provide a completely shielded inductive device for use at radio frequencies in which device the winding or windings and the shield are so disposed that the shielding is attained without high eddy-current losses. A further object is to provide an inductive coupling device having windings thereon which constitute two separate electrical circuits and in which the leakage of magnetic flux between the windings is maintained at a minimum regardless of the absolute magnitudes of the involved self- and mutual inductances, and more specifically an object is to provide a novel form of winding material particularly adapted for use in the construction of coupling devices of the type stated.

These and other objects of our invention will be apparent from the following description when considered in connection with the accompanying drawings which illustrate various embodiments of our invention, and in which—

Fig. 1 is a perspective view of a vario-transformer embodying our invention;

Fig. 2 is a perspective view of the rotor, Fig. 3 is a perspective view of one of the stator elements,

Fig. 4 is a sectional detail in perspective and illustrating the double winding in position on the rotor,

Fig. 5 is a perspective view of a shielded transformer, as viewed from the rear end,

Fig. 6 is a similar perspective view, partly in section, as taken from the front of the shielded vario-transformer,

Fig. 7 is a vertical section through the rear closure of the shield,

Fig. 8 is a perspective view, partly in sec-

tion, of a modified form of shielded vario-transformer, and

Fig. 9 is a vertical section through a stator and rotor, illustrating a modification in the construction of the stator elements.

In the drawings the rotor is designated by the numeral 1 and comprises a portion of a right circular cylinder having parallel recesses 2, 2 extending around the outer face thereof for receiving windings. If desired, the rotor body may be slotted as at 3 to reduce the amount of material employed and to facilitate the winding operations, but this feature is not essential. The rotor 1 is provided with shafts 4, 4 which are preferably hollow and serve as conduits for the terminals of the windings. The shaft 4' is of sufficient length to extend beyond the stator and serve as a support for an operating knob or dial 5 and is provided with a transverse opening 6 through which one set of terminals passes.

For convenience in manufacture and assembling, the stator preferably comprises two L-shaped members 7 having inner faces which conform to the shape of the outer surface of the rotor 1. The inner surface of each stator member comprises a thin web 8 which is preferably a thin sheet of micarta or similar material, i. e., paper impregnated with a phenolic condensation product. To adequately support the thin web 8 and to define spaces for receiving windings, three parallel ribs 9 are arranged on the web members. The stator members 7 are conveniently formed by a molding operation in which the plastic composition, rubber, phenolic resin or the like, which is to form the ribs 9, is united to a pre-shaped web 8 which has been placed in a mold of the proper design. At the proper point, the central rib 9 of each stator member 7 is provided with an opening 10 which serves as a bearing for a shaft of the rotor, and the two members 7 when assembled about the rotor may be held in position by suitable means, such as screws 11.

In variable inductive coupling devices, the closeness of the coupling between those portions of the windings carried respectively by rotor and stator, when the device is adjusted to give maximum or minimum coupling, is a material factor affecting the effective range

of inductance of the windings which may be secured. If the stationary and movable windings could be brought into contact at each end of the range of variation, optimum results would be attained, but it is obvious that this cannot be attained with a coupling device comprising a stator and a rotor. The construction as described above permits a very close approximation to such an arrangement however, since the web 8 which separates the stator winding from the rotor need not exceed 1/64 inch in thickness and may be thinner. The depth of the recesses 2, 2 of the rotor is so designed that the windings will lie just within the outer circumferential surface of rotor. Some small clearance may be allowed between the rotor and the web 8, but with careful construction such clearance is not necessary and the rotor may be supported by and journaled within the web 8 of the stator. When no clearance is provided between the stator and rotor the adjacent faces of the stator and rotor windings will be spaced apart by a distance not materially greater than 1/64 of an inch and even this small clearance between the windings may be still further reduced by the use of a thinner sheet of material for the web 8. This provides an approach to physical coincidence of the stator and rotor portions of the two windings in their coplanar positions, which results in the close approximation to unity coupling which is necessary for an extended inductance range of both primary and secondary windings.

When the maximum range in inductance of the windings is not essential, the clearance between the stator and rotor windings may be increased, as by providing clearance between the rotor and stator or by the use of thicker sheets for the web 8. Alternatively, the thin web which separates the stator windings from the inner face of the stator member may be formed of the same material as the ribs. Such a construction is shown in Fig. 9, in which the web 8', as well as the ribs 9, is formed of hard rubber, phenolic resin or the like.

The stator and rotor bodies may be used to support any desired type of winding, i. e. they may be wound to provide a variocoupler or a vario-transformer. When wound as a vario-transformer the stator and the rotor each carry a portion of the primary and of the secondary windings and the two portions of each winding are connected in series.

When no clearance is provided between the rotor and stator it is evident that the double windings must be carefully and compactly arranged upon the rotor, as otherwise the outer layer might rub against the stator. By using a cable or double wire consisting of two insulated strands laid parallel to each other and encased without twisting or

weaving in a thin layer of insulating material, the windings may be readily applied to the rotor. In Fig. 4, the two parallel strands of wire 12 are separated from each other by insulating material 13 which may be enamel or a wrapping of silk or cotton and the two wires are bound together by a silk or cotton wrapping 14. In addition to the mechanical advantages resulting from the use of a double wire of this construction, an electrical advantage is also obtained, since the capacity between the primary and secondary windings has no effect upon the currents traversing the windings. This follows from the fact that substantially unity coupling between the primary and secondary windings is obtained at all positions of the rotor; consequently, there is no difference in potential between adjacent points of the two windings, and no flow of current across the dielectric between adjacent turns. With these conditions the electrostatic capacity existing between the two windings has no effect upon the current flow.

To protect audions or other devices adjacent the coupling device from being influenced by the electric and magnetic fields set up by the passage of current thru the windings it is desirable to employ a shield around the same. Although it has been generally believed that concentrated inductance windings traversed by radio frequency currents could not be shielded by adjacent continuous metal shields, we have discovered that little or no loss in the efficiency of a concentrated radio frequency inductance will result when the field is of proper form and the shield is properly spaced from the windings. Complete shielding without material loss in efficiency and without unduly increasing the overall dimensions of the device may be attained when the shield is so spaced from the windings that the magnetic field at points adjacent the inner surface of the shield is substantially parallel to said inner surface. In the form illustrated in Figs. 5-7, the shield comprises a section of square tubing 15 of metal such as iron, brass, or copper, surrounding the coupling device. The cap or closure 16 at one end of the tube 15 is provided with a central aperture 17 through which the shaft 4' of the rotor passes. The cap 16 bears an index mark 18 for cooperating with an appropriate scale on the dial 5, and also a stop lug 20 which projects within an arcuate slot 21 formed in the rear face of the dial. The cap 22 at the opposite end of the tube 15 carries binding posts 23 which are insulated from the cap 22 and which serve as terminals for the primary winding. The terminals of the secondary windings are similarly attached to another set of binding posts 24, 24' which are also carried by the cover 22. The low end of the secondary is grounded to the met-

al shield, preferably by means of a strip 25 carried by the binding post 24' and contacting with the cover 22. It is obvious that the same result may be obtained by omitting the insulation between the binding post 24' and the cover 22, but it is desirable from the standpoint of convenience in assembling to employ the same mounting for all of the binding posts. The size and shape of the 10 stator and shield may be such that the stator fits snugly within the shield, but preferably spacing lugs 26 are provided for positioning the stator within the shield and these lugs may be integral with the stator members 7 15 or they may be attached to the stator members in any desired manner.

In Fig. 8, we have shown a modified form of shield and coupling device. The main body of the shield in this instance comprises 20 a thin tube 27 of circular cross-section having closures 28 and 29 which correspond respectively to the closures 16 and 22 which are employed with the rectangularly shaped shield. The outer surface of the stator members 25 is shaped to the curvature of the inner surface of the tube 27 and the size of the stator is such that it may fit snugly within the tube. To position the stator within the casing a strip 30 having a width equal to that 30 of a recess 2 in the stator may be soldered inside the tube 27. The stator may be spaced from the end closures by spacing lugs on the stator similar to the lugs 26 as above described or by projections on the inner 35 face of the closures, which projections may also serve to position the closures with respect to the body of the shield. In this and with the square shield, the closures may be secured to the shield by soldering or brazing.

40 It will be noted that the windings are elongated, having a length which is materially greater than their width, and that the enclosing shield is so positioned by the ribs of the stator that the shield is spaced from the windings and its axis is substantially coincident with the axis of the windings. In actual use we have found that such a shield may be employed with windings 45 traversed by currents at a frequency as high as 1500 kilocycles (200 meters) with complete elimination of external fields and without excessive eddy-current losses.

50 While the specific embodiments of our invention as herein described relate to vario-transformers having rotors comprising portions of right circular cylinders, it is to be understood that the invention is not limited to vario-transformers nor is it limited to inductive coupling devices employing rotors of this specific shape. It is apparent that 55 many changes which may be made in the various parts, their relative size, shape and position fall within the scope of our invention.

We claim:

1. An electro-magnetic coupling device of the type described, comprising two relatively movable elements, and primary and secondary windings formed by twin conductors on said elements, said relatively movable elements comprising concentric surfaces of revolution, the outer element including a thin web carrying spaced ribs, forming grooves for receiving the windings. 70

2. An electro-magnetic coupling device as 75 claimed in claim 1, in which the two relatively movable elements have the form of right circular cylinders of which the length exceeds the diameter.

3. An inductive coupling device for use in 80 radio frequency circuits comprising a web of non-conducting material, a winding thereon suitable for the conduction of radio frequency currents, a metallic envelop enclosing said web and winding and shielding the 85 same, and ribs of dielectric material on said web, spacing said envelop from said winding.

4. A variable inductive coupling device 90 comprising a rotor having the form of a portion of a right circular cylinder, whose length is materially in excess of its diameter, a stator having an inner surface conforming to the shape of said rotor, primary and secondary windings arranged on said rotor and stator, a metallic envelop having the 95 form of a right circular cylinder enclosing said windings and shielding the same, and means on said stator spacing the inner surface of said envelop from the outer layers 100 of said windings and positioning said envelop with its axis substantially coincident with the axis of said rotor, stator and the windings thereon.

5. In a variable coupling device a stator 105 assembly comprising two similar L-shaped members fitting together to form a stator element comprising a thin web conforming to a portion of a surface of revolution and ribs upon the exterior of said web arranged to form grooves for the reception of the windings.

6. In a variable coupling device a rotor having an outer face conforming to a portion 110 of a surface of revolution, and a stator comprising two L-shaped elements fitting together to present interiorly a surface of revolution concentric to that of said rotor.

7. In a variable inductive coupling device 115 comprising two relatively movable elements and windings thereon, a metallic shield surrounding said elements and spaced from the outer element by means of ribs forming grooves for the reception of the windings.

120 In testimony whereof, we affix our signatures.
